RESILIENT WHEEL.

1,021,515.

Specification of Letters Patent. Patented Mar. 26, 1912.

Application filed January 8, 1912. Serial No. 669,975.

To all whom it may concern:

Be it known that I, CARROLL D. GALVIN, a citizen of the United States, residing at Merchantville, county of Camden, State of

5 New Jersey, have invented a new and useful Resilient Wheel, of which the following is a specification.

10 My present invention relates to resilient wheels and consists in its broad and generic scope of a novel demountable felly, which is secured at its inner periphery to a pneumatic tube or cushion, and at its outer periphery to a tread member of any desired or conventional construction.

15 It further consists of a novel construction of a demountable felly which is substantially inclosed within the pneumatic tube or cushion employed.

20 It further consists of a novel construction of a demountable felly with which coöperates a novel construction and arrangement of an inflatable tube.

25 It further consists of a novel construction of a demountable felly which may be readily assembled and removed with respect to the rim of the wheel body, the inner portion of such detachable felly being recessed in such a manner that by the air compression when the tube is inflated, it interlocks around and 30 under projecting shoulders of the felly, the inner face of the detachable felly being constructed concentric to the outer face of the wheel rim, thus becoming a riding member for the wheel body in case of deflation, without resultant injury to the wheel construction or stoppage for repair or injury to the 35 pneumatic tube.

40 It further consists of a novel construction of an inflatable tube, the inner periphery of which is provided with terminals, which interlock with the fixed rim and the fastening devices therefor, while the outer periphery of the inflatable tube interlocks with the detachable felly member and the fastening devices coöperating with such felly and with the tread, it being noted that the inflatable tube is thus directly connected with the fixed felly member and with the detachable felly member, so that the inner periphery of the 45 two will be held in suspension.

50 It further consists of a novel construction of a pneumatic tube and a novel manner of securing the same in position with respect to the other parts of the device.

It further consists of other novel features 55 of construction, all as will be hereinafter fully set forth.

For the purpose of illustrating my invention, I have shown in the accompanying drawings one form thereof which is at present preferred by me, since the same had been found in practice to give satisfactory and reliable results, although it is to be understood that the various instrumentalities of which my invention consists can be variously 65 arranged and organized and that my invention is not limited to the precise arrangement and organization of these instrumentalities as herein shown and described.

Figure 1 represents a sectional elevation 70 of a portion of a resilient wheel embodying my invention. Fig. 2 represents a side elevation of a portion of my device. Fig. 3 represents a sectional elevation similar to Fig. 1. Figs. 4 and 5 represent sectional 75 views showing details of the construction.

1 designates the spokes which are secured with respect to the fixed rim or inner felly 2 in any desired manner, said fixed rim or felly 2 being provided with inwardly converging sides 3, the inner portions of which are recessed as indicated at 4. The outer periphery of the fixed rim 2 has secured thereto in any desired manner a metal tire 5, the side faces of which are preferably rounded as is indicated at 6.

7 designates clamping disks which are provided with a laterally extending flange 8 adapted to interlock with the recesses 4 of the fixed rim 2, said disks 7 being secured in assembled position by means of draw bolts 9 provided with nuts 10, said rods 9 passing through the fixed rim 2 and also through the inner terminals 11 of the inflatable tube 12, which will now be described. This tube 95 is preferably constructed of alternate layers of fabric and rubber and comprises the driving disks 13, the inner terminals 11 of which have embedded therein the cores 14, thereby forming non-compressible wedge-shaped terminals which interlock with the clamping plates 7 and the fixed rim 2. The outer periphery of the side disks 13 has embedded therein the non-compressible cores 15, thereby forming wedge-shaped terminals 100 16, which are interlocked with a novel construction of an outer demountable felly 17 in a manner hereinafter explained. The

outer portion or layer of the pneumatic tube 12 is vulcanized or otherwise secured at its various points of contact as at 18 to the side members 13 of the tube 12 in order to prevent relative movement between the inner and outer layers of material which form the tube.

19 designates strips of soft rubber or other suitable material, the inner ones of which 10 engage the curved face 6 of the tire 5, it being seen that the inner periphery of the tube 12 is seated upon the tire 5. The outer periphery of the inner layer of the pneumatic tube is centrally split as indicated at 15 20 and is stitched or otherwise secured together as indicated at 21. The demountable felly 17 is recessed as indicated at 22, thereby forming shoulders 23, the inner periphery of which is concentric to the face 24 of the tube 12.

25 designates a layer of any desired material which engages the side faces and the inner periphery of the demountable felly 17 for its reinforcement, it being noted that 25 the inner periphery of said demountable felly 17 is centrally recessed as indicated at 26 in order to receive the ends of the pneumatic tube and prevent creeping of the latter. The side walls of the demountable 30 felly near their outer periphery are beveled inwardly as is indicated at 27, thereby adapting the same to interlock with the wedge-shaped terminals 16 and the clamping rings 28, which latter are secured with 35 respect to the felly 17 by the draw-bolts 29 passing therethrough, and also through the terminals 16 and the clamping rings, such bolts being provided with fastening means, such as the nuts 30.

40 31 designates the outer rubber tread which is vulcanized on to a hard rubber base 32, which is further dove-tailed on to a serrated metal base or tire 35. 33 designates reinforcing dowels which fix the felly 17 to 45 the tread and prevent creeping of the outer tread on the felly. 34 designates a valve controlled conduit of any desired or conventional type which passes through the fixed rim, 2, the tire 5, and the inflatable tube 50 12 in order that such tube may be inflated or deflated as desired. I preferably also employ set screws 36 which engage the clamping plate 28 and the metal body portion of the tread 35. The clamping plates 55 7 are curved downwardly and outwardly as indicated at 37 in order to partially encompass the cushioning zone of the tire, and preferably terminate at a point beyond the inner periphery of the demountable felly 60 17 in order to resist the side thrust of the tread member.

Special attention is directed to the manner in which the inflatable tube is split at its outer periphery thereby enabling one 65 to vulcanize additional material on the in-

ner face of the tube in case the same should at any time become necessary by the re-opening of said tube.

In brief conclusion of the salient functions of my novel construction of demountable felly in combination with its inflatable tube and its exterior tread, I obtain direct drive for the transmission of power from the body member to the outer tread by means of the wedge-shaped terminals interiorly and exteriorly placed upon said combination of tube and shoe. By thus placing the pneumatic tube within the rigid exterior felly of the wheel, I form a circular shock absorber within the wheel itself, whereby all rebound shock is absorbed at right angles to its point of occurrence by the opposite segment of the pneumatic tube. By this novel construction by means of distributing the load over an increased part of the confining walls 85 of the rigid exterior felly, I am enabled by said distribution of weight to carry my load at one-fifth of the air pressure per square inch of tube as found in actual practice as compared to the air pressure required to 90 carry similar load upon pneumatic tubes placed exterior to its felly as in present practice.

By forming the transverse shoulders in the outer felly, cushioning upon the juxtaposed contortions of the pneumatic tube as shown in drawing, I obtain a resisting leverage to counteract by the air pressure any unnatural deviation or side-thrust of the outer tread in skidding.

I also call special attention to the fact that by this novel construction, I am enabling the outer tread under speed to retain its natural vertical plane of momentum, leaving the body member of the wheel to 105 instantaneously adjust itself automatically with the line of its axle on striking chuck-holes or road obstructions without interrupting the gyroscopic plane of its outer tread periphery.

It will be noted that by a novel construction of parting the pneumatic tube in manufacture for the purpose of vulcanization upon the mold and by my system of refastening the two ends of the tube, I may by 115 this novel construction proceed at any time to reopen the pneumatic tube for purposes of repair or investigation without injuring the functions of said tube upon reassembling.

It will be understood that the inner tube 12 may be constructed of any desired number of layers of fabric and rubber which may be arranged alternately or in any other desired manner, and the driving disks 13 may be constructed in a similar manner as is most clearly seen in Figs. 4 and 5, from which it will be apparent that the driving disks 13 are composed of alternate layers of rubber and fabric 37 and 38, respectively,

and that the core 14, preferably of hard rubber, is interposed between the layers of fabric 38 to form the wedge-shaped terminal 11 which forms a continuation of one of the layers of rubber 37*. It will be understood that the spokes 1 are secured in any desired manner with respect to a hub 39 of any desired or conventional type. The inflatable tube 12 may also be constructed of any desired number of layers of fabric and rubber and arranged in any desired manner, and in Fig. 4 I have shown the same as consisting of layers of rubber 40 and of fabric 41.

It will now be apparent that although I have shown the inner layer of the inflatable tube as being secured to the outer layer of driving disks at the various points of contact, that in the broad scope of my invention the driving disks and the inner tube 20 may be entirely separate and distinct and still be within the broad scope of my invention.

It will now be apparent that I have devised a novel and useful construction of a resilient wheel, which embodies the features of advantage enumerated as desirable in the statement of the invention and the above description, and while I have, in the present instance, shown and described a preferred embodiment thereof which has been found in practice to give satisfactory and reliable results, it is to be understood that the same is susceptible of modification in various particulars without departing from the spirit 35 or scope of the invention or sacrificing any of its advantages.

Having thus described my invention, what I claim as new and desire to secure by Letters Patent, is:—

40 1. In a resilient wheel, the combination of an inner felly, an outer felly having outer and inner portions and recesses in its sides and also having a recess in its inner periphery, and an inflatable tube having an inflated annular portion interposed between the inner and outer fellies, and inwardly directed inflated portions occupying the side recesses of the outer felly, and also having end portions seated in the recess in the inner 50 periphery of the outer felly.

2. In a resilient wheel, the combination of an inner felly, an outer felly having outer and inner portions and recesses in its sides and also having a recess in its inner periphery, and an inflatable tube having an inflated annular portion interposed between the inner and outer fellies, and having inwardly directed inflated portions occupying the side recesses of the outer felly and also 55 having its outer peripheral portion split and its end portions secured together and seated in the recess in the inner periphery of said outer felly.

3. In a resilient wheel, the combination 60 of an inner felly, an outer felly having outer

and inner portions and side recesses between the same and also having a recess in its inner periphery, a pneumatic tube having an inflated portion disposed between the fellies and inwardly directed inflated portions disposed in the side recesses of the outer felly and also having end portions secured together and disposed in the recess in the inner periphery of the outer felly, inner terminals 70 on the tube and connected with the inner felly, and outer terminals on the tube and connected with the outer felly.

4. In a resilient wheel, an inner felly having outwardly diverging side walls, an outer felly having outer and inner portions, and recesses in its sides and an annular recess in its inner periphery, an inflated tube having an inflated annular portion interposed between the inner and outer fellies and having inwardly directed inflated portions occupying said side recesses of said outer felly, said tube having its outer peripheral portion split and its juxtaposed end portions secured together and seated in said recess in said inner periphery of said outer felly, means for securing said tube to said outer felly, side plates having the flaring portions 85 37 and the inwardly extending flanges 8, and fastening devices common to said inner felly and side plates.

5. In a resilient wheel, an inflatable tube, means for securing the inner periphery of said tube in position, a detachable metal covered felly having annular side recesses forming T-shaped shoulders at its inner 100 periphery interlocking with the outer inwardly contorted periphery of said tube when inflated, and a tread secured to said detachable felly.

6. In a resilient wheel, an inner fixed felly, 105 an inflatable tube adapted to seat on said inner felly and having inner terminals, means for interlocking said terminals with the sides of said inner felly, an outer felly having annular side recesses forming shoulders contained within said tube and with which said tube interlocks by air compression when inflated, said tube having outer terminals adapted to interlock with the sides of said outer felly, an annular recess 110 26 in said outer felly, said tube being split and having its terminals seated in said recess 26 and secured together, a tread, and means for securing said tread and said outer terminals with respect to said outer felly. 115

7. In a resilient wheel, an inner fixed felly, an inflatable tube having terminals at its inner periphery, means for securing said terminals with respect to said inner felly, said tube having terminals at its outer periphery, a detachable felly covered with a reinforcing layer, a tread, means for securing said outer terminals and tread with respect to said detachable felly, the latter being 120 substantially inclosed within said tube and 125 130

adapted to interlock therewith, when inflated.

8. In a resilient wheel, an inner fixed felly, an inflatable tube seated thereon and provided with terminals extending along the sides of said felly, clamping disks for interlocking said terminals with said felly, an outer felly having annular side recesses forming projecting shoulders, the inner peripheries of which are concentric with the outer periphery of said inner felly, said tube interlocking with said outer felly to prevent relative movement with respect thereto, said outer felly having an annular recess 26 therein, said tube having its outer peripheral portion split and its juxtaposed end portions secured together and seated in said recess 26, and a tread member secured to said outer felly and said tube.
9. In a resilient wheel, the combination of an inner fixed felly, an outer felly, substantially T-shaped in cross section, driving disks secured at their outer periphery to the outer felly, clamping disks for securing the

driving disks at their inner peripheries to the inner fixed felly and partially overhanging the driving disks, an inflatable tube within said driving disks, and engaging the inner portion of the driving disks in proximity thereto to form with the sides of the T-shaped felly juxtaposed annular side walls for the cushioning of side thrust, annular side plates clamping the outer periphery of said driving disks to said outer felly, a tread carried by said outer felly, transverse draw bolts holding the inner clamping disks and the inner peripheries of the driving disks in assembled position with regard to the fixed felly, and transverse draw bolts holding the outer annular side clamping plates, and the outer peripheries of the driving disks in assembled position with regard to the outer felly.
